UNITED STATES PATENT OFFICE

FRITZ GIEHLER, OF CHEMNITZ, GERMANY

SHUTTLE

Application filed December 1, 1928, Serial No. 323,001, and in Germany December 3, 1927.

My invention relates to improvements in weaver's shuttles, and the object of the improvements is to provide a shuttle in which the picking stick acts on studs projecting from the side of the shuttle, and preferably from the front side thereof. When disposing the said studs on the front side of the shuttle they are located between the bearings of the spool and the points of the shuttle. By thus operating the shuttle it is not necessary to reinforce the points of the shuttle, and yet the said points are not subject to wear. Further, spoiling of the goods by oil from the picking stick is avoided.

For the purpose of explaining the invention an example embodying the same has been shown in the accompanying drawing, in which the same letters of reference have been used in all the views to indicate corresponding parts. In said drawing,

Fig. 1, is an elevation of the shuttle, and Fig. 2, is a plan view thereof.

In the example shown in Fig. 1 the shuttle is provided at its front side with studs k^1 , k^2 located between the bearings of the spool and the ends of the shuttle. In Fig. 1 I have shown one of the picking sticks acting on the stud k^2 , the said stick being operated from a cam e through the intermediary of a tongue z carried by the stick. The shuttle is provided at its top and bottom sides with the usual longitudinal grooves r^1 and r^2 by means of which it is guided while flying through the shuttle-race. Conventional means may be provided for journalling the spool within the shuttle, one form of such means being indicated at p in the drawing. It will be noted that the studs k^1 and k^2 are disposed between the supporting means p and the ends of the shuttle.

The studs k^1 and k^2 are fixed to the body of the shuttle. In the operation of the shuttle the picking sticks s strike on the studs k^1 and k^2 . Thus no blow is exerted on the points of the shuttle, so that reinforcing of the said points is not necessary.

The spools are mounted on the front side of the shuttle, the figures showing the usual peg p .

I claim:

1. A shuttle, comprising the body, and studs projecting laterally from the body and adapted for engagement by the picking sticks.

2. A shuttle, comprising the body, means for supporting the spool mounted on said body, and studs projecting laterally from said body and located between said means and the ends of the body.

In testimony whereof I hereunto affix my signature.

FRITZ GIEHLER.
